(No Model.)

T. HOLLAND.
STEAM RADIATOR.

No. 404,353.

Patented May 28, 1889.

UNITED STATES PATENT OFFICE.

TIMOTHY HOLLAND, OF ST. PAUL, MINNESOTA, ASSIGNOR TO MARY C. HOLLAND, OF SAME PLACE.

STEAM-RADIATOR.

SPECIFICATION forming part of Letters Patent No. 404,353, dated May 28, 1889.

Application filed June 30, 1888. Serial No. 278,674. (No model.)

To all whom it may concern:

Be it known that I, TIMOTHY HOLLAND, a citizen of the United States, residing at St. Paul, in the county of Ramsey and State of Minnesota, have invented certain new and useful Improvements in Steam-Radiators, of which the following is a specification.

This invention relates to radiators connected into systems of steam-heating apparatus; and it consists in the construction and arrangement, as hereinafter shown and described, and specifically pointed out in the claims.

In the drawings, Figure 1 is a side elevation, partially in section, of one of the radiators constructed according to my improved method. Figs. 2 and 3 are end views of slightly-different forms of the hollow sections detached. Fig. 4 is a plan view of the radiator shown in Fig. 1, the upper parts of three of the tubes being in section on the line X X of Fig. 1. Figs. 5 and 6 are detail views of a portion of a nest of radiators, showing the construction whereby two sets of the double tubular sections may be coupled together.

The sections forming the radiator may be made of any material or form, but will preferably be made of cast-iron of the form shown. The sections each consist of a U-shaped flat tube, the two main branches A' A² being united at their tops by a cross branch, a, and with free communication between the two sections at their bottoms b. The sections are united to each other and to the main supply and discharge piping B' by short sections of piping B², the lowest line of the latter being above the highest point in the bend at the lower ends of the tubular section, so that a water seal is formed by the accumulation of the water of condensation in the lower end of each section to prevent the steam from passing around the lower bends of the tubular sections. The steam is thus forced to pass upward through one branch, A', and downward through the other branch, A², throughout all the sections continuously, so that the circulation is constant and free and the accumulation of air-pockets effectually prevented and all danger of the radiator becoming "air-bound" avoided.

Another important advantage obtained by this construction is that every particle of the surface of all the sections is "radiating-surface," thus obtaining from the steam the benefit of all the heat which is transmitted into the walls of the radiator. This advantage is also true of the parts containing the water seal, as the water therein is kept at a high temperature, while by the form of the sections no large masses of water occur at any point, but every part of the radiator is accessible to the surrounding atmosphere, which is therefore free to absorb all the heat which is radiated therefrom.

In Figs. 5 and 6 are shown two views of portions of two sets of the radiator-tubes coupled together, so that a double line of the sections may be connected to one feed-supply. Two of the tubes A' A² are united at their lower ends by a cross branch, A³, the feed-pipe F being connected into this cross branch, and the remainder of the sections, which go to make up the complete radiator, coupled to these tubes A' A², as in Figs. 1 and 4. By this means a double-tubed radiator may be formed with only one inlet, F.

If the "return" or discharge is to be by a separate system of piping, both ends of the sets of sections will be supplied with one of the coupled pair of tubes; but in a single-connection system, or one in which the water of condensation is "returned" by the same piping which supplies the steam, only one of the coupled pair of tubes will be employed. By this arrangement one of the double radiators containing the same number of square feet of heating-surface may be placed within one-half the length of space occupied by one of the single radiators, which is of great advantage where economy of space and compactness are desirable.

Another advantage obtained by this double arrangement is that the sections may be formed with a smaller radiating-surface, so that the area of heating-surface may be increased in smaller ratio without so greatly increasing the floor-space occupied by the radiator.

To illustrate, it is not economical in prac-

tice to form the sections singly, as in Figs. 1 and 2, with less than four square feet of radiating-surface, which would enable me to form radiators with eight, twelve, sixteen, twenty, 5 or twenty-four square feet of surface, and so on; but it frequently happens that rooms are met with which require radiating-surface equal to the intermediate areas—such as ten, fourteen, eighteen, or twenty-two square feet; 10 and in order to secure these it is necessary to form sections having smaller square feet of radiating-surface; but such small sections occupy so much space when a number of them are coupled together that it is of great advantage to couple them in pairs, and thus secure the required-sized radiators without needlessly lengthening them.

Under some circumstances the branch A³ may be extended so as to connect three or 20 more of the sets of sections A' A², and I do not wish to be limited to any fixed number.

I am aware that it is not new to form radiators with water seals in their lower portions or bases, and I do not therefore claim, broadly, 25 a radiator containing a water seal, the novelty in my invention consisting in the construction whereby each radiator-section is complete in itself and contains its own independent water seal, the radiator as a whole being made up of a series of these independent double 30 tubes connected together, and whereby the desired result is accomplished.

Having thus described my invention, what I claim as new is—

35 1. A radiator composed of separately-formed sections arranged in series, each section hav-

ing in one piece two vertical branches—an inlet branch and an outlet branch—said branches being connected at their tops to form a passage for the steam, and being formed at 40 their bottoms with a connecting trap-bend, in combination with horizontal connecting pipes or nipples connecting the outlet branch of one section with the inlet branch of the succeeding section, said connecting pipes or nipples 45 being located above the highest point of the trap-bends in said sections, substantially as set forth.

2. A radiator comprising a plurality of rows of radiating-sections, each of said sections having in one piece two vertical branches—an inlet branch and an outlet branch—said branches being connected at their tops to form a passage for the steam, and being formed at 50 their bottoms with a connecting trap-bend, 55 horizontal connecting nipples or pipes connecting the outlet branch of one section of each row with the inlet branch of the succeeding section of the same row, said connecting nipples or pipes being located above the highest point of the trap-bends in said sections, in combination with a single cross steam-inlet section connected with the initial radiating-section of each of the several rows of sections, 60 substantially as set forth.

In testimony whereof I have hereunto set my hand in the presence of two subscribing witnesses.

TIMOTHY HOLLAND.
